(57) CLAIM

The ornamental design for a handle, as shown and described.

DESCRIPTION

FIG. 1 is a front perspective view of a handle showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a front perspective view of the handle of FIGS. 1-7 and including a symbolic break between its end portions.

FIG. 9 is a front view thereof;

FIG. 10 is a rear view thereof;

FIG. 11 is a top view thereof;

FIG. 12 is bottom view thereof;

FIG. 13 is a right side view thereof; and,

FIG. 14 is a left side view thereof.

The broken lines immediately adjacent to the shaded area define the bounds of the claimed design and form no part thereof.

The bracket in FIGS. 8-14 symbolically represents a disclaimed break between its claimed end portions and the appearance of any portions between the break lines forms no part of the claimed design.

The small circular broken lines in FIGS. 3 and 10 illustrate portions of the article and form no part of the claimed design.
